UNITED STATES PATENT OFFICE.

HAMILTON EDWARD HARWOOD, OF JOLIMONT, VICTORIA, AUSTRALIA,
ASSIGNOR TO FREDERICK WILLIAM HARWOOD, OF JOLIMONT,
AUSTRALIA.

METHOD OF AND MEANS FOR TREATING THE SURFACE OF THE PERMANENT WAY OF RAILWAYS, &c.

No. 832,973.

Specification of Letters Patent.

Patented Oct. 9, 1906.

Application filed July 14, 1906. Serial No. 326,230.

To all whom it may concern:

Be it known that I, HAMILTON EDWARD HARWOOD, a subject of the King of Great Britain, residing at "Moller," Palmer street, 5 Jolimont, in the State of Victoria, Australia, have invented certain new and useful Improvements in Methods of and Means for Treating the Surface of the Permanent Way of Railways, &c.; and I do declare the following to be a full, clear, and exact description of the invention, such as will enable others skilled in the art to which it appertains to make and use the same.

This invention has been devised to provide a method and means for preserving the surface of that portion of railways known as the "permanent way," wherein the rails are fastened to sleepers, said sleepers being held in their position by ballast consisting of stones or the like. The means employed by me will also prevent the growth of weedy vegetable matters upon such sleepers and ballast.

In order that my invention may be the more easily understood, reference may be made to the accompanying drawings, in which—

Figure 1 is an elevation of one form of apparatus suitable for carrying my invention into effect, while Fig. 2 is a plan view of the subject of Fig. 1.

In the drawings, A is a steam-spray jet upon the back or front of a locomotive B, said jet drawing from a supply-tank, as C, a mixture of tar and arsenic, preferably in a heated condition. The engine B proceeds slowly along the line and the spray D is blown by the nozzle or nozzles in the jet A so as to cover the ballast E and sleepers F with a coating of the said tarry arsenious mixture. When a small section of the line has been so sprayed, I lay upon such sprayed surface a compound consisting approximately of about ten pounds of arsenic to two hundred and fifty gallons of tar and to which is added and incorporated cinders, small coke, ashes, gravel, or the like media sufficient to form a thick mixture capable of slowly flowing. This mixture is preferably distributed by a mechanical spreader or with hand-rakes. Occasional 50 perforations should be allowed at intervals which will enable any rain-water falling upon such parts to escape. After the ballast E and sleepers F have been covered to, say, a

quarter of an inch in thickness or thereabout the tar and arsenic spray D, hereinbefore mentioned, is repeated.

When the engine is performing the final spraying, the sand-box G is brought into requisition and the wheel H on axle operates the chain J so that the latter may revolve 60 the pulley K of a sand-feeder L, which in revolving allows sand to flow in an even film down between guide-plates M onto the newly-tarred surface caused by the spray D as the engine B moves along.

In order that the rails shall not be coated by the spray, a metal shield N is placed over each one. The shields are attached to a hanging plate N', the latter being fixed to the bed-plate of the locomotive B.

It will be understood that where my invention has been employed a permanent way, treated as I have described and hardened by exposure, will not form a congenial ground for grassy or weedy growths. The arsenic being inimical to plant life will kill all seeds or roots already on the sleepers or ballast and prevent any fresh germinations. A line thus treated will not generate dust when the train is passing, so that there will consequently be less wear and tear upon the axles and boxes and the machinery of the locomotive generally owing to absence of such frictional matter. A saving in lubricant and economy of power will thus also be arrived at.

Having thus described my invention, what I claim, and desire to secure by Letters Patent, is—

1. The method of preserving the surface of permanent way on railways and the like and preventing weedy growths thereon, consisting essentially in the employment of a locomotive machine which sprays finely-disseminated arsenic and tar in a heated condition upon the ballast and sleepers, applying a layer upon such sprayed surface of a tar compound when the latter is set, again spraying the whole surface except the rails with heated tar and distributing upon the surface of such heated tar, sand or the like powdered earth, substantially as and for the purposes set forth.

2. The method herein specified of preserving the surface of the permanent way on railways and the like and preventing weedy growths thereon, consisting in spraying the

- surface of all the permanent way except the rails with tar, then laying upon such sprayed surface a compound of arsenic, tar and coke or the like media and when such mixture is set spraying its surface with the arsenic and tar in a heated condition and distributing over the surface of same a covering of sand or pulverized earth for drying purposes, substantially as and for the purposes set forth. 20
- 10 3. In a means for preserving the surface of the permanent way on railways and the like and preventing weedy growths thereon, and in combination, a tar-supply tank, means for heating such tar, a spraying jet or device, a 25 locomotive for conveying the parts along the rails of the way and shields for protecting the rails, a sand or earth tank and means for delivering the sand or earth, substantially as and for the purposes set forth. 30
- 15 4. In a means for preserving the surface of the permanent way on railways and the like and preventing weedy growths thereon, and in combination, a locomotive as B, shields as N, a steam tar-distributing spray device as A, a tar-tank as C, means for heating the said tar, a sand or pulverized earth-box as G, having therein a dredge-roller operated by sprocket-chain as J, from a pinion upon an axle as H, and guide-plates as M, substantially as and for the purposes set forth.

In testimony whereof I have signed my name to this specification in the presence of two subscribing witnesses.

HAMILTON EDWARD HARWOOD.
